a corporation of New York

Application October 13, 1953, Serial No. 27,163

Term of patent 7 years

(Cl. D9—2)

To all whom it may concern:

Be it known that I, Alan Daniels, a citizen of United States of America, residing at 300 Central Park West, New York city, in the county of New York and State of New York, have invented a new, original, and ornamental Design for a Brush, of which the following is a specification, reference being had to the accompanying drawing, forming part thereof.

In the drawing:

Fig. 1 is a side elevational view of a brush showing my new design;

Fig. 2 is a bottom plan view thereof; and

Fig. 3 is a front view.

The dominant part of the design herein resides in the portion shown in full lines.

I claim:

The ornamental design for a brush, substantially as shown and described.
